UNITED STATES PATENT OFFICE.

CHARLES M. HAYNES, OF CHILLICOTHE, OHIO.

MEANS FOR ADJUSTING LENS-MOUNT STRAPS.

1,263,412.

Specification of Letters Patent. Patented Apr. 23, 1918.

Application filed August 31, 1916. Serial No. 117,842.

To all whom it may concern:

Be it known that I, CHARLES M. HAYNES, a citizen of the United States, residing at Chillicothe, Ohio, have invented certain new 5 and useful Improvements in Means for Adjusting Lens-Mount Straps, of which the following is a full, clear, and exact description.

In mounting spectacle and eyeglass lenses 10 in "rimless" frames it is frequently found that the straps that embrace the lens edges do not fit the latter, the space to receive the lens being too wide or too narrow. It is then necessary for the optician to compress or 15 expand the straps. In doing so it is evident that he must be careful to keep the screw holes in alinement. My present invention relates to this operation, and its object is to provide simple and inexpensive means 20 for the purpose whereby the straps can be easily and quickly bent to fit the particular lens. To this and other ends the invention consists in the novel features and combinations hereinafter described.

25 One form of the invention is illustrated in the accompanying drawing, in which—

Figure 1 is a perspective view of the preferred form of gage member.

Fig. 2 is a side view showing the gage 30 member combined with a suitable pair of pliers, as used in accordance with my invention.

Fig. 3 is a detail view showing a lens-mount with its straps compressed by the device shown in Fig. 2.

In its preferred form my invention involves the use of a pair of pliers, say of the parallel-jaw type shown at 10. With the pliers I combine a gage member 11, consisting of a flat plate of metal 12 provided with side wings 13. The device is slipped on one jaw of the pliers, the said wings being spaced so as to embrace the sides of the jaw rather snugly to prevent accidental 45 displacement. If the wings fit the jaw too loosely they can be bent toward each other slightly, by means of the pliers. The plate 12 is long enough, and extends far enough above the wings, to extend slightly beyond 50 the end of the plier-jaw, as clearly shown in Fig. 2. A number of gage members (as many as may be necessary or desirable) are provided, with their plates 12 of different thicknesses, each corresponding to a stand- 55 ard lens-thickness.

To explain the use of the device, it is assumed that (as is usually the case) the lens-mount straps 14 are spaced too far apart to fit the particular lens, and hence must be bent toward each other. The optician then 60 selects the gage member having a lens-plate of the same or slightly less thickness than the lens, and fits it to the plier-jaw as shown in Fig. 2. One strap of the lens-mount is then inserted between the lens-plate 12 and 65 the inner face of the jaw and the mount is pushed down as far as it will go, so that the end of the lens-plate is at the bend of the strap. The plier-jaws are now brought firmly together. In this operation the 70 straps are bent toward each other, but their approach is limited by the intervening lens-plate. Then when the mounting is removed the straps will be found to be shaped somewhat as shown in Fig. 3, spaced apart the 75 proper distance to receive the lens-edge and with the screw-holes 15 in alinement.

Sometimes the optician finds the straps too close together, for example in fitting new lenses to old mounts. In such case they can 80 be forced onto the lens-plate 12; or, if too close together for that, they can be spread apart by prying with the side of a screwdriver or the back of a knife blade, etc. The operation above described then gives 85 the straps the proper spacing and shape for the lens.

So far as my experience goes, the straps are always bent about equally; or at any rate such inequality as may exist has not 90 been sufficient to put the screw holes appreciably out of alinement.

It is to be understood that the invention is not limited to the specific devices herein shown and described but can be embodied in 95 other forms without departure from its spirit.

I claim:

Means for adjusting lens-mount straps, comprising a pair of pliers, and a device 100 consisting of a flat plate between the plier-jaws having a pair of side wings movably embracing one of the jaws, whereby the device is self-adjusting when used as described and is instantly removable to permit use of 105 the pliers in the ordinary way for other purposes.

In testimony whereof I hereunto affix my signature.

CHARLES M. HAYNES.
